UNITED STATES PATENT OFFICE.

HIRAM HERRICK, OF BOSTON, MASSACHUSETTS.

IMPROVEMENT IN PIANO-FORTES.

Specification forming part of Letters Patent No. **80,073**, dated July 21, 1868.

To all whom it may concern:

Be it known that I, HIRAM HERRICK, of Boston, in the county of Suffolk and State of Massachusetts, have invented a new and useful Improvement in Piano-Fortes; and I do hereby declare the same to be fully described in the following specification and represented in the accompanying drawings, of which—

Figure 1 is a top view of a piano-forte with the lid removed provided with my invention. Fig. 2 is a transverse section of it with the lid in place. Fig. 3 is a front elevation of the piano as open—that is, with its upper frame, sounding-board, and strings raised off the action and into vertical positions.

In carrying out my improvement I arrange the sounding-board, the wrest-pin block, and the bridges underneath the iron frame and above the strings. I also arrange the iron frame, the sounding-board, the wrest-pin block, and the strings and the action in two separate cases, hinged together, so as to enable the said iron frame, sounding-board, and strings to be turned up or off the action, so as to uncover it and bring the strings into a convenient position to enable access to be had to either of them. I also not only insert the straining, tuning, or wrest pins through the iron frame, so that their heads or ends to which the tuning-key is applied may project upward from the frame and the lower ends of such pins may project downward from the frame and wrest-pin block, but I apply the strings to those parts of the said pins which project below the wrest-pin block. Furthermore, I combine with each string and its tuning-pin one or more auxiliary adjusters, as hereinafter described, the purpose of such being to enable the string to be tuned to a nicer degree than by its tuning pin or pins.

From the above it will be seen that I have in some respects reversed the usual mode of constructing piano-fortes. I have found that the tone emitted from the back of a sounding-board is much fuller and purer than that from the side next the strings, and therefore in square and grand pianos I place the rear side of the sounding-board upward. Another advantage resulting from my arrangement is that I get all the action underneath the strings without the necessity of carrying any part of it through the iron frame or sounding-board. This enables the iron frame to be braced in any

manner as strongly as may be desirable without interfering with any of the parts below it. As no part of the iron frame goes below the strings, the hammers can be arranged at equal distances asunder, without breaks between them, as heretofore has been required in the ordinary construction of piano-fortes.

In the drawings the piano-case is represented as formed in two cases, A B, one of which is placed on the other, and both are hinged together at their rear sides, as shown at *a a* in Fig. 3.

In the drawings I have shown but one key, *b*, with its fly *c*, hammer *d*, and damper *e* in a contracted or distorted state to what they would be in practice.

The action is wholly arranged within the lower case, B.

Within the upper case, A, to which the cover or lid *C* is hinged, I arrange the iron frame *D*, the sounding-board *E*, and the wrest-pin block *F*, the bridges *G H*, the hitch-pin plate *I*, and the strings *K*. The iron frame is directly over the sounding-board and the bridges and strings are placed underneath such board.

One of the hitch-pins is shown at *f* and two of the tuning-pins are shown at *g g*. These pins go through the iron frame *D* and the wrest-pin block *F*, and project above the former and below the latter, the string being wound on those parts of the tuning-pins which extend below the wrest-pin block. The upper parts of the tuning-pins are to be made in the ordinary way for reception of the tuning-key.

The auxiliary adjuster hereinbefore mentioned consists of a hook or rod, *h*, having a screw cut on its upper part and a hook or eye at its lower part to embrace or receive the string. This adjuster extends up through the wrest-pin block and the iron frame and between the bridge and the tuning-pin, and has a nut, *i*, screwed on that part of it which extends above the said frame. By screwing down the nut against the iron frame that part of the string which is between the bridge and the tuning-pin will be drawn up and bent out of a right line, so as to increase the tension of the string. By such auxiliary means of producing tension of the string the latter may be tuned to much better advantage than by the tuning-pin alone.

I claim as my invention the following—that is to say:

1. The improved arrangement of the sound-

ing-board, the wrest-pin block, and the bridges with respect to the iron frame and the strings, such sound-board, strings, wrest-pin block, and bridges, under such an arrangement, being placed underneath the iron frame and above the strings.

2. The combination of the two separate cases A B, hinged together as described, with the action arranged on the lower one and the sounding-board and strings placed in the upper one, as set forth.

3. The combination of the auxiliary adjuster with the string, the tuning-pin, and bridge.

4. The improved arrangement of the tuning-pins with the strings and the wrest-pin block, or the same and the iron frame, the tuning-pin, under such arrangement, having its head to extend from one side of the said block, and having the string applied to the part which projects from the other side of the block, the whole being substantially as set forth.

HIRAM HERRICK.
